(57) **CLAIM**

The ornamental design for a transmission casing, as shown and described.

DESCRIPTION

FIG. 1 is a first perspective view of our transmission casing; FIG. 2 is a top plan view of our transmission casing;

FIG. 3 is a bottom plan view of our transmission casing;

FIG. 4 is an end view of our transmission casing showing the end illustrated in FIG. 1;

FIG. 5 is a side view of our transmission casing showing the side illustrated in FIG. 1;

FIG. 6 is a second perspective view of our transmission casing showing the transmission casing in a position rotated 180° relative to FIG. 1;

FIG. 7 is a second end view of our transmission casing showing the flange end; and,

FIG. 8 is a second side view of our transmission casing showing the side illustrated in FIG. 6.
